UNITED STATES PATENT OFFICE.

GEORGE S. LEE, OF HAWTHORNE, NEW JERSEY, ASSIGNOR, BY MESNE ASSIGNMENTS, TO THE NATIONAL AIR-BRAKE COMPANY, OF NEW YORK, N. Y., A CORPORATION OF NEW JERSEY.

AIR-BRAKE.

SPECIFICATION forming part of Letters Patent No. 557,511, dated March 31, 1896.

Application filed December 21, 1895. Serial No. 572,890. (No model.)

To all whom it may concern:

Be it known that I, GEORGE S. LEE, a citizen of the United States, residing at Hawthorne, in the county of Passaic and State of New Jersey, have invented certain new and useful Improvements in Air-Brakes; and I do hereby declare the following to be a full, clear, and exact description of the invention, such as will enable others skilled in the art to which it appertains to make and use the same.

My invention has relation to air-brakes, and has for its object the provision of an automatic governor adapted to govern and control that class of air-brakes in which air for the operation of the brake is compressed and stored in a reservoir by a pump and mechanism for communicating motion to the pump from the axle of the car, the construction and operation of my improvement being such that when any desired maximum degree of pressure has been attained the governor will disconnect the pump-operating mechanism, and when the pressure has fallen to any desired minimum the governor will reconnect the pump-operating mechanism so the compression and storage of air will be resumed.

In applications for patents pending concurrently with the present I have described in detail the construction and operation of the several mechanical structures which constitute the complete air-brake, and in the following specification I will specifically describe the construction and operation of the automatic governor and briefly refer to so much of the other parts of the complete organization as may be necessary to a proper understanding of the governor.

Referring to the accompanying drawings, Figure 1 is a central longitudinal sectional view of the governor. Fig. 2 is a longitudinal section on the line xx of Fig. 1; Fig. 3, a central longitudinal section on the line yy of Fig. 1.

A A' designate hollow cylindrical members secured together by a screw-coupling and constituting a cylinder larger at one end than the other, the larger section A having its end closed by a head A^2 , provided with a stuffing-box A^3 , through which passes a piston-rod carrying two pistons A^5 and A^6 , the former

fitting and working in the larger part A of the cylinder, while the latter fits and works in the smaller part A' .

The piston-rod is formed in two sections A^7 and A^8 , attached together by a screw-coupling, 55 and the piston A^5 is formed integral with the section A^7 , while the piston A^6 is integral with the section A^8 . Suitable packing a^3 a^6 is applied to the respective pistons, which move simultaneously as an integral structure. A 60 lever F is pivotally connected to the end of the piston-rod A^7 , and is also connected to and by its movement serves to connect and disconnect the clutch which is interposed between the axle of the car and the pump. 65 Upon the end of the cylinder is screwed a valve-chamber B , having two valve-seats b^1 and b^2 and valves b^3 b^4 , formed on a stem b^4 , the valves seating oppositely to one another, so that as one is closed the other is opened. The 70 stem b^4 extends beyond the valve b^3 and is socketed to receive the end of a follower b^5 , which is carried by a compression-spring b^6 , contained in a casing b^7 , the other end of spring b^7 bearing on a flanged screw-plug b^8 , 75 which screws through the head b^9 of the casing b^7 , and by means of which the tension of the spring b^6 is regulated.

A pipe C leads from the valve-chamber to a compressed-air reservoir, and a branch-pipe C' leads from the pipe C to a chamber C^2 , containing pressure-regulating valves arranged on the side of the section A of the cylinder. This chamber C^2 is cylindrical in cross-section, and contains three piston-valves C^3 C^4 C^5 , mounted on a sectional stem C^6 , and the stem and valves are pressed toward the end of the chamber into which the pipe C' enters by a compression-spring C^7 , that bears against the valve C^3 and at the other 90 end bears against a flanged screw-plug C^8 , that screws through the head C^9 of the chamber and serves as a means for adjusting the tension of the spring. A by-pass pipe D is connected with the chamber C^2 above and 95 below the valve C^5 , and a valve D' is arranged in said by-pass pipe, being pressed against its seat d by a compression-spring d' , and the stem d^2 of the valve projects into the chamber above the valve C^5 , a beveled surface d^3 100

on the end of the stem contacting with a beveled surface c on the valve C^5 , serving to close and hold firmly in position the valve D' when the valve C^5 is moved by the pressure of air 5 in pipe C' .

Operation: When, by the rotation of the car-axle and consequent operation of the pump, the pressure in the air-reservoir has reached a maximum of, say, fifty-one pounds, 10 the valve b^2 , the function of which is to admit air under predetermined pressure to the cylinder A' , will be opened against the pressure of spring b^6 , which has been regulated by means of the screw-plug b^9 to exert a closing pressure of fifty pounds on the valve b^6 , while the valve b^3 , which controls the exhaust from the chamber A^{11} , will be closed and the air will enter under the piston A^6 , and will force up the piston-rod $A^7 A^8$, and operate the 15 lever F to throw out of engagement the clutch that connects the driving-axle and pump, thereby stopping the pump. Prior, however, to this operation, and after a pressure of thirty-six pounds has been gained, the air 20 will have entered the chamber C^2 through pipe C' , and forcing up the valves $C^3 C^4 C^5$ will have closed the valve D' in the by-pass pipe D and opened a port f , leading from cylinder A to the space in chamber C^2 before 25 the valves C^3 and C^4 , from which space there is a free passage to the open air through a port f' . When the pump is stopped at fifty pounds pressure by the movement of piston-rod $A^7 A^8$ and pivoted lever F , the pump will 30 remain inactive until the air-pressure has been reduced sufficiently to allow the spring C^7 , which has been regulated to exert a pressure of thirty-five pounds, to push down the stem C^6 and open the valve D' of the by-pass 35 pipe D , and allow air to enter the cylinder A , above the piston A^5 , through a port f^8 , whereby the piston is depressed to its seat on the end of cylinder-section A' , and the pump is set in motion by the downward pull of the 40 piston-rod A^7 on the lever F .

The foregoing operations are repeated automatically from time to time as the pressure in the air-reservoir reaches the desired maximum or minimum, and thus the proper and 45 safe pressure requisite for efficient operation is constantly preserved.

Having described my invention, I claim—

1. In a governor for air-brakes, the combination with a chamber containing pistons of 50 different areas, of means for admitting air at

different pressure alternately and automatically in contact with said pistons to operate the same, substantially as described.

2. In a governor for air-brakes, the combination of a chamber having sections of different area, pistons of different area fitting 60 said chamber, a spring-valve adapted to admit air under determined pressure to the piston of lesser area, and a spring-valve adapted to admit air at a lower determined pressure 65 to the piston of greater area, substantially as described.

3. In an automatic governor for air-brakes, the combination of a chamber in sections of different areas, pistons working in said chambers, means for automatically admitting air under pressure to the piston of smaller area and automatically releasing the air from the chamber of greater area and means for cutting off the supply of air at high pressure releasing the air from the chamber of lesser area and simultaneously admitting air at lower pressure to the piston of greater area, substantially as described. 70

4. In an automatic governor for air-brakes, 80 a chamber in sections of different area, pistons fitted thereto and mounted on a common rod, a valve admitting air at a predetermined maximum pressure to one of said pistons, a valve connected to the supply-pipe operable 85 by a decrease of pressure to a predetermined minimum and a third valve operable by the said valve on the supply-pipe to admit air under the minimum pressure to the other of said pistons, substantially as described. 90

5. In an automatic governor for air-brakes, the combination with a cylinder and piston, of a valve controlling the inlet and exhaust on one side of said piston and automatically operable by air under low pressure to open 95 the inlet and close the exhaust and by air under high pressure to close the inlet and open the exhaust, with a second valve controlling the inlet and exhaust on the outer side of said piston and operating to open and close the inlet and exhaust on that side under reverse 100 conditions of air-pressure, substantially as described.

In testimony whereof I affix my signature in presence of two witnesses.

GEORGE S. LEE.
